UNITED STATES PATENT OFFICE.

BERTHA A. BRIDGES, OF LEESVILLE, SOUTH CAROLINA.

CLOTHESPIN.

1,337,434.

Specification of Letters Patent. Patented Apr. 20, 1920.

Application filed August 5, 1918. Serial No. 248,372.

To all whom it may concern:

Be it known that I, BERTHA A. BRIDGES, a citizen of the United States, residing at Leesville, in the county of Lexington, State 5 of South Carolina, have invented certain new and useful Improvements in Clothespins; and I do hereby declare the following to be a full, clear, and exact description of the invention, such as will enable others 10 skilled in the art to which it appertains to make and use the same.

The present invention relates to new and useful improvements in clothes pins more particularly of that type formed of a single 15 length of wire bent to provide a pair of gripping loops adapted to receive therebetween a clothes line and article to be held thereon.

It is in general the object of the invention 20 to simplify and otherwise improve the structure of clothes pins of this type, and it is more particularly the object to provide an arrangement insuring a maximum gripping action of the jaws or loops of the clothes 25 pin.

With the above and other objects and advantages in view, the invention resides more particularly in the novel combination, formation and arrangement of parts herein- 30 after described and particularly pointed out in the appended claim.

In the accompanying drawings:

Figure 1 is a perspective view of the improved clothes pin.

Fig. 2 is an edge elevational view thereof. Fig. 3 is a sectional view therethrough on the line 3—3 of Fig. 1.

Fig. 4 is a side elevational view of the clothes pin.

Referring now more particularly to the drawings, the improved clothes pin is formed of a single length of wire bent to provide two oval coils or loops 5 and 6 respectively the loop 6 having its major and 45 minor diameters both smaller than those of the loop 5.

The ends of the wire meet at one side of the pin adjacent its end which is uppermost in operation and said ends and the loops are 50 secured together at this point by twisting the ends at 7 about the adjacent intermediate stretch of the wire, which extends in one direction from this connection to form what might be called the inner side 8 of the larger 55 or outer loop 5 and extends in the other direction to form the normally upper end of the smaller or inner loop 6.

The other or outer side 9 of the loop 5 is given a twist to produce a small loop or eye 10 standing in a horizontal plane when the 60 planes of the main loops are substantially vertical, and this eye projects out of the plane of its loop 5 toward the plane of the other loop 6, although it is adapted to pass it because the loop 5 is larger than the loop 65 6 and hence the eye is more remote from the connection 7 at the inner sides of the loops than is the outer side of the smaller loop 6. The loop 5 is also provided with a bent portion 11 below the convolutions bowed in the 70 same direction. The eye 10 forms a stop shoulder for engagement with a clothes line inserted between the loops from below, and the bent portion 11 forms a hump coating with said shoulder to receive the line be- 75 tween them.

Thus, in the application of the clothes pin, a clothes line and article to be held thereon are inserted between the lower ends of the loops, this insertion being facilitated by the 80 extension of the loop 5 below the loop 6. The outer side of the pin is then forced downwardly over the line and article until the line abuts the stop shoulder 10. With this stop shoulder is a fulcrum, the pin may 85 then be rocked downwardly to firmly wedge the line between the inner sides of the loops, the line being held from displacement between the loop sides adjacent the shoulder by the bowed portion 11. 90

An exceedingly simple and durable clothes pin has thus been provided which may be applied to a clothes line and article held thereon in a most ready and convenient manner and insuring a firm and positive secure- 95

ment.

What is claimed is:

The herein described clothes pin comprising a pair of wire loops of different size rigidly connected at one side to lie normally 100 in parallel planes, one loop at its free side formed with a stop shoulder standing in a plane transverse to this loop and projecting toward the other loop and with a hump adjacent said shoulder and coating therewith 105 to hold a clothes line, as set forth.

In testimony whereof, I affix my signature, in the presence of two witnesses.

BERTHA A. BRIDGES.
